PULL

La Verne E. Clayton, Rockford, Ill., assignor to Amerock Corporation, Rockford, Ill., a corporation of Illinois

Filed June 5, 1963, Ser. No. 75,220

Term of patent 14 years

(Cl. D10—8)

FIGURE 1 is a front elevational view of a pull, incorporating my new design.

FIG. 2 is a top plan view of the pull.

FIG. 3 is a side view of the pull as viewed from the left in FIG. 1.

FIG. 4 is an enlarged sectional view taken along the line 4-4 in FIG. 1.

I claim:

The ornamental design for a pull, substantially as shown.
